CLAIM

The ornamental design for a backpack, as shown and described.

DESCRIPTION

FIG. 1 is a perspective view of a backpack, showing my new design in a fully closed configuration;

FIG. 2 is a perspective view thereof, showing a top flap in a raised configuration;

FIG. 3 is a perspective view thereof, showing a top compartment in an open configuration to reveal five object holders;

FIG. 4 is a perspective view of the object holders, the remaining portions of the backpack omitted for clarity of illustration;

FIG. 5 is an exploded top plan view of FIG. 3 and the object holders of FIG. 4;

FIG. 6 is a front elevational view of FIG. 1;

FIG. 7 is a rear elevational view of FIG. 1;

FIG. 8 is a left-side elevational view of FIG. 1;

FIG. 9 is a right-side elevational view of FIG. 1;

FIG. 10 is a top plan view of FIG. 1;

FIG. 11 is a bottom plan view of FIG. 1;

FIG. 12 is a front perspective view thereof, showing a left compartment in an open configuration;

FIG. 13 is a perspective view of FIG. 2, and further showing two front compartments each in an open configuration; and,

FIG. 14 is a rear perspective view of FIG. 1.

The dot-dash broken lines in FIG. 5 depict portions of the backpack that form no part of the claimed design. The remaining dash-dash broken lines depict stitching, and do form part of the claimed design.

1 Claim, 14 Drawing Sheets
